UNITED STATES PATENT OFFICE.

ALBERT H. LOEBS, OF MIDDLETOWN, N. Y., ASSIGNOR TO WHEELER, MADDEN,
& CLEMSON MANUFACTURING COMPANY, OF SAME PLACE.

DESIGN FOR SAW-BLADES.

SPECIFICATION forming part of Design No. 11,752, dated April 27, 1880.

Application filed March 24, 1880. Term of patent 14 years.

To all whom it may concern:

Be it known that I, ALBERT H. LOEBS, of Middletown, in the county of Orange and State of New York, have originated a Design 5 for Saw-Blades, of which the following is a full, clear, and exact description, reference being had to the accompanying drawing, making part of this specification.

My invention relates to a new and original 10 design for hand-saws; and it consists, essentially, in a hand-saw having its blade provided with a triangle miter-protractor, which is formed on the saw-blade by stamping, etching, or in any other manner desired.

15 The accompanying drawing illustrates a view, in side elevation, of a hand-saw embodying my design.

A represents the triangle, and B the miter-protractor.

20 The triangle may be formed of any desired size, and the miter-protractor located within the triangle and graduated to enable the operator to lay out any desired angle.

The design may be stamped or etched on 25 any portion of the blade of the saw, but is preferably located near the handle. The lines of the design are sunk slightly below the surface of the saw-blade, and hence cannot be effaced or impaired by the continued use or 30 wear of the saw.

If desired, the lines may be filled in with any substance which will form a strong contrast in color to the blade of the saw, and thus enable the design to be readily and easily distinguished.

35 Instead of forming the design by stamping or etching, it may be formed by means of the sand-blast, and produce the lines with a dead surfacing, which may be easily distinguished.

40 The object of placing the design upon the blade of a saw is to lessen the number of separate tools and instruments essential to a complete kit of carpenters' tools, as a separate

protractor and triangle may be dispensed with by forming the design on the blade of the 45 saw. This results in a material saving in first cost, as the saw is not materially enhanced in price by forming the design in question on the saw-blade; and, further, it obviates the necessity for carrying about a separate instrument 50 to lay out the angles in mitering.

The triangle miter-protractor, when stamped or otherwise formed on the saw-blade, may be utilized in a number of different ways.

A bevel may be applied to the miter-protractor, and the desired angle secured, and then transferred to the work to be done; or the saw-blade may be placed upon the work and the angles laid off by means of a square or straight-edge. The saw-blade, being thin, is 60 especially adapted for the purpose in view, as the measurements can be readily indicated on the work in hand on opposite edges of the saw-blade.

It is evident that the location and form of 65 the design may be varied somewhat without departing from the essence of my invention.

The triangle may be dispensed with, and the base of the miter-protractor placed at the upper edge or back of the saw-blade.

Having fully described my invention, what I 70 claim as new, and desire to secure by Letters Patent, is—

1. A design for hand-saws, consisting of a miter-protractor formed on the saw-blade, substantially as set forth.

2. A design for hand-saws, consisting of a triangle miter-protractor formed on the saw-blade, substantially as set forth.

In testimony that I claim the foregoing I 80 have hereunto set my hand.

ALBERT H. LOEBS.
